All y,

JEROME SCOTT, OF CHARLESTON, PENNSYLVANIA.

Letters Patent No. 83,325, dated October 20, 1868.

IMPROVED WASHING-MACHINE.

The Schedule referred to in these Letters Patent and making part of the same.

To all whom it may concern:

Be it known that I, JEROME SCOTT, of Charleston, in the county of Tioga, and State of Pennsylvania, have invented a new and improved Washing-Machine; and I do hereby declare that the following is a full and exact description thereof, reference being had to the accompanying drawings, and the letters of reference marked thereon, in which—

Figure 1 is a perspective view of the machine, with the handle E slightly raised, and

Figure 2 a sectional view of the same, taken on the line *x x* of fig. 1.

Similar letters of reference indicate corresponding parts.

The nature of my invention consists in the manner in which I hang, connect, and operate, in my washing-machine, a swinging bucket and press-board, which are made to approach and depart from each other alternately, by the up-and-down movement of the handle.

To do this, I build my tub oblong, with an arc-shaped bottom, as shown at A, in the accompanying drawings, although the tub can be made square and flat-bottomed, if desired. From the bearings B', set in the top of the sides, B, of the tub, I hang, by means of the axle C, the swinging-lever bucket, D, which is moved backward and forward through the tub by means of the handle E, set between the levers F. The bottom of this bucket is shaped to an arc corresponding with the bottom of the tub, and part of the boards forming its bottom are left slightly apart, so as to form the openings f, for the purpose of permitting the water to pass from the bucket into the tub as it is squeezed from the clothes. The boards forming the back of the bucket are corrugated for the purpose of presenting uneven surfaces to the clothes, and are left apart in the same manner as the bottom boards, although holes can be used to carry off the water from the bucket, if desired. From the sides of the tub are run up the supports R, and braces G. From the bearings g, in the top of the support R, is hung the press-board, H, by means of its arms I and axle J. This press-board has its cross-boards corrugated and separated in the same manner and for the same purpose as the back-boards of the swinging bucket, and is connected to the levers F of the swinging bucket by means of the arms K. When the machine is not in operation, the front of the press-board H lies close

against the inside of the back of the swinging bucket D, and both on a line perpendicular with the top of the tub, and in its centre. When the handle E is raised, the swinging-bucket D is drawn towards the end of the tub marked 1. This movement of the swinging bucket throws the ends of the levers F, and the arms K attached to them at a, towards the end of the tub 2, and the other ends of the arms K, being attached to the arms I of the swinging press-board H, at b, the press-board is also pushed back towards that end of the tub, thus separating it from the swinging bucket. When thus separated, the clothes are placed in the bucket D, and the handle E is pressed down, which brings together the press-board H, and the inside of the back of the bucket D, thus squeezing the clothes between them. The handle E is then raised, which causes the bucket and the press-board to move in opposite directions, as before stated. This movement causes the clothes to fall from the back of the bucket, up against which they were pressed by the press-board, down in its bottom, where they lie until the handle E is moved down, when they are again pressed up against the back of the bucket by means of the press-board, as before shown, and are consequently turned by every upward motion of the handle E, and pressed by every downward motion. The bearings, B and g, are left open at the top, to admit of the removal of the axles C and J therefrom. The axle J is provided with the hooks m, by means of which it is hooked down to the supports R. N is a spicket to let off the water from the tub, and o are its legs.

What I claim as my invention, and desire to secure by Letters Patent, is—

The swinging bucket D, as arranged and connected, by means of the arms K, with the press-board H, and operated by the levers F and handle E, substantially in the manner and for the purposes herein shown and described.

In testimony that I claim the foregoing invention, I have hereunto set my hand, this 5th day of September, 1868.

JEROME SCOTT.
